UNITED STATES PATENT OFFICE.

ALPHONSE PELLETIER, OF NORWALK, CALIFORNIA.

BURGLAR ALARM.

Application filed October 6, 1921. Serial No. 505,704.

To all whom it may concern:

Be it known that I, ALPHONSE PELLETIER, a subject of the King of Great Britain, residing at Norwalk, in the county of Los Angeles and State of California, have invented new and useful Improvements in Burglar Alarms, of which the following is a specification.

My invention relates to a burglar alarm of the type wherein a cartridge or like explosive member is utilized for giving a warning signal when the alarm device is actuated, the principal objects of my invention being to provide a relatively simple and practical device that may be positioned at any desired point within a room or building, said device containing a cartridge and being provided with means for striking and exploding said cartridge, and further to provide connections from said cartridge striking means to all of the doors, windows and other openings in the room or building, so that should an attempt be made to enter any of the doors or windows, the cartridge striking means will be released, thereby exploding the cartridge and giving an alarm.

With the foregoing and other objects in view, my invention consists in certain novel features of construction and arrangement of parts that will be hereinafter more fully described and claimed and illustrated in the accompanying drawings, in which:

Fig. 1. is a perspective view of the corner of a room and showing a burglar alarm of my improved construction positioned on the floor of the room with connections leading from said alarm to the doors and windows of the room.

Fig. 2. is a side elevational view of the burglar alarm of my improved construction.

Fig. 3. is a vertical section taken through the center of the alarm device.

Fig. 4. is an enlarged vertical section taken on the line 4—4 of Fig. 2.

Referring by numerals to the accompanying drawings which illustrate a practical embodiment of my invention, 10 designates the base plate of the device, the end portions thereof being provided with apertures 11, that are adapted to receive screws or like fastening devices when the alarm device is anchored to a fixed object.

Formed in the center of plate 10 is an opening 12, and extending upwardly from said plate, directly in front of said opening

is a transversely disposed plate 13 in which is formed an aperture 14.

Formed integral with and projecting upwardly to the sides of opening 12, and to the rear of plate 13 are plates 15, between which is arranged for operation a cartridge striking member or hammer 16, and which latter is pivotally mounted on a pin 17 that is seated in the plates 15.

Projecting forwardly from the front edge of hammer 16, is a lug 18 that is adapted to pass through aperture 14, and strike against the cartridge that is positioned in the device.

Formed integral with the rear portion of hammer 16 and projecting outwardly and upwardly therefrom is a short arm 19, and projecting downwardly and rearwardly from the lower portion of said hammer is a lug 20.

Secured in any suitable manner to the top of plate 10 behind the end of opening 12 is one end of a flat spring 21, the free end of which extends forwardly through opening 12 and said free end bears directly against the edge of lug 20, and the lower end of hammer 16.

Pivots connected to plates 15 to the rear of hammer 16 is a hammer retaining device comprising a plate 22, the lower portion of which is provided with an opening 23 that is adapted to receive the end of arm 19 when the hammer is turned rearwardly into "set" position, and the upper end of said plate 22 is provided with an aperture 24 to which is connected one end of a flexible member 25.

This flexible member may be in the form of a strong cord or small wire cable, and it is led from the alarm device through suitably located screw eyes, or like supports, across windows, doors, skylights, and other openings, the arrangement being such that if any of the windows or doors are opened or partially opened, the flexible member 25 will be drawn away from the alarm device so as to disengage plate 22 from the arm 19 of hammer 15, and consequently permitting said hammer to be swung forward against plate 13 under the influence of spring 21.

Formed on the forward end of plate 10 are laterally projecting ears 26 that serve as a support for the rear end of a barrel 27, the latter being provided at its rear end with a chamber 28 that is adapted to receive a blank cartridge.

One side of the rear portion of the bar-

rel 27 is provided with a laterally projecting lug 29 that is pivotally connected to one of the ears 26 by a pin or rivet 30, thereby enabling the barrel to be swung horizontally 5 into a position at right angles to the plate 10 so that a cartridge may be positioned within or removed from chamber 28.

Formed on the other side of the rear portion of barrel 27 is a laterally projecting 10 ear 31 that is adapted to overlie the corresponding ears 26, and formed through these ears, are apertures 32 that are adapted to receive a retaining device, preferably a cotter pin 33.

15 To load and set my improved burglar alarm, cotter pin 33 is withdrawn to permit barrel 27 to be swung into a position at right angles to plate 10, and secured in such position by the insertion of cotter pin 20 33 through apertures 32. Hammer 16 is now drawn rearwardly, and the arm 19 is engaged by retaining plate 22.

As the hammer is thus drawn rearwardly in the "set" position, lug 20 on the lower 25 end of said hammer bears downwardly on the free end of spring 21, thereby placing said spring under tension.

As retaining plate 22 is swung into position to engage the arm 19 of hammer 16, the 30 flexible member 25 is drawn into taut condition, and thus the device is "set" or made ready for operation.

In the event that any of the protected 35 windows or doors are opened, flexible member 25 will be drawn away from the alarm device, thereby disengaging plate 22 from the arm 19, and the power stored in spring 21 will throw the hammer forwardly so that lug 18 will strike against the rear end of the 40 cartridge, thereby exploding the latter and giving an alarm.

The burglar alarm of my improved construction is relatively simple, may be easily 45 and cheaply produced, and is very effective in performing its intended functions.

It will be understood that minor changes 50 in the size, form and construction of the various parts of my improved burglar alarm, may be made and substituted for those herein shown and described without departing from the spirit of my invention, the scope of which is set forth in the appended claims.

I claim as my invention:

1. In a burglar alarm, a base, a barrel pivotally mounted on said base and adapted to swing in a horizontal plane, said barrel being provided with a cartridge receiving chamber, a hammer pivotally mounted on the base and adapted to engage the cartridge 55 positioned within the barrel, a pivotally mounted member on the base for engaging and retaining the hammer in set position, and means for moving said member to disengaging position with respect to said hammer.

2. In a burglar alarm, a base, a barrel pivotally mounted on said base and adapted to swing in a horizontal plane, said barrel being provided with a cartridge receiving chamber, a hammer pivotally mounted on the base and adapted to engage the cartridge positioned with the barrel, a pivotally mounted member on the base for engaging and retaining the hammer in set position, and a flexible member connected to the hammer retaining member for moving the latter to releasing position. 70 75

3. In a burglar alarm, a base plate, a plate projecting upwardly from said base plate, there being an opening formed in said upwardly projecting plate, a barrel pivotally connected to the base plate, and adapted to swing in a horizontal plane, the rear portion of said barrel being provided with a cartridge receiving chamber, the rear end of which communicates with the opening in the vertically disposed plate, a spring actuated hammer pivotally mounted on the base plate to the rear of the vertically disposed plate, and having a portion that is adapted to pass through the opening in said vertically disposed plate, and releasable means for retaining the hammer in a predetermined position. 80 85 90 95

4. In a burglar alarm, a base plate, a plate projecting upwardly from said base plate, there being an opening formed in said upwardly projecting plate, a barrel pivotally connected to the base plate, and adapted to swing in a horizontal plane, the rear portion of said barrel being provided with a cartridge receiving chamber, the rear end of which communicates with the opening in the vertically disposed plate, a spring actuated hammer pivotally mounted on the base plate to the rear of the vertically disposed plate, 100 105 110 which hammer is provided with a portion that is adapted to pass through the opening in said vertically disposed plate, a hammer retaining member pivotally mounted on the base plate for engaging and retaining said hammer in set position, and means for moving said member to a releasing position with respect to the hammer. 115

5. In a burglar alarm, a base plate, a plate projecting upwardly from said base plate, 120 125 130 which hammer is provided with a portion that is adapted to pass through the opening in said vertically disposed plate, a spring actuated hammer pivotally mounted on the base plate to the rear of the vertically disposed plate, which hammer is provided with a portion that is adapted to pass through the opening in said vertically disposed plate, a hammer retaining member pivotally mounted on the base plate for engaging and retaining said

hammer in set position, and a flexible member connected to said hammer retaining member for moving the latter to releasing position.

6. A burglar alarm comprising a plate projecting upwardly from the base and having an opening formed therein, a barrel sustained on the base and provided with a cartridge receiving chamber which communicates with the opening in said plate, a spring actuated hammer pivotally mounted on the base to the rear of said plate and having a pin that is adapted to pass through the opening in said plate, and releasable means for retaining the hammer in a predetermined position.

7. A burglar alarm comprising a base, a plate formed on the base having an opening therein, a barrel pivoted on the base to occupy one position in which its bore is in

registration with the opening in said plate and another extreme position in which the bore is disposed at an angle with respect to the opening of said plate to allow of the insertion or removal of the cartridges to or from the bore, a hammer pivoted to the base and including a pin adapted to extend through the opening in said plate against the cartridge when the hammer is in active position, means normally retaining the hammer in inactive position, means for urging the hammer to an active position, and means for moving the first means to releasing position whereby the second means is allowed to function.

In testimony whereof I have signed my name to this specification.

ALPHONSE PELLETIER.
